[57] **CLAIM**

The ornamental design for a display panel or similar article, substantially as shown and described.

DESCRIPTION

FIG. 1 is a perspective view of a display panel or similar article, showing my new design;

FIG. 2 is a right side elevational view thereof;

FIG. 3 is a left side elevational view thereof;

FIG. 4 is a top plan view thereof;

FIG. 5 is a bottom plan view thereof;

FIG. 6 is a front elevational view of a second embodiment of a display panel or similar article.

The rear surface of the display panel or similar article is substantially planar and unornamented.

FIG. 1

FIG. 2

FIG. 3

FIG. 4

FIG. 5

FIG. 6
